CONVERTIBLE PLAYGROUND APPARATUS

Homer R. Robbins, Amarillo, Tex., assignor to
E. Y. Brown, Fort Worth, Tex.

Application February 17, 1950, Serial No. 144,825

1 Claim. (Cl. 272—60)

1

This invention relates to playground equipment, or amusement apparatus, especially designed for children, and it has particular reference to apparatus which is formed or made up in such a manner as to be adaptable to rearrangement in different forms, affording units having different characteristics, and the principal object of the invention resides in the provision of playground or exercising apparatus, such as that shown and described in a co-pending application filed by applicant herein on September 5, 1946, and bearing Serial No. 694,982, now Patent No. 2,616,485 and to which reference is made herein for a further description of the invention.

Another object of the invention is that of affording equipment of the character described which may be economically constructed and is capable of considerable flexibility in which several different devices for the entertainment and amusement of children may be readily and easily formed and utilized on playgrounds, in amusement parks, and the like, whereby children may be properly exercised and entertained without undue hazards.

Broadly, the invention contemplates the provision of apparatus which may embody the form of a swing, a trapeze, a slide, teeter-totter, sled, and other devices, by the simple rearrangement of parts which are detachably assembled and which are capable of being reassembled in different forms, as desired, with a minimum of difficulty.

While the foregoing objects are paramount, other and lesser objects will become manifest as the description proceeds, taken in connection with the appended drawings, wherein:

Figure 1 is a side elevational view of a complete unit formed by the invention, illustrating a frame supporting a ladder on which is arranged a teeter-totter.

Figure 2 is a plan view of the teeter-totter assembly employed in the structure shown in Figure 1, illustrating a seat on each end.

Figure 3 is an end view of the assembly illustrated in Figure 1.

Figure 4 is a side elevational view of a slide in which the parts are arranged to position the base member in an inclined position, the ladder unit being arranged to provide means for climbing to the upper end of the slide.

Figure 5 is an end view of another arrangement of the assembly, illustrated in Figure 7, in which a pair of ladders are employed and connected at their lower ends.

Figure 6 is a rear elevational view of the as-

2

sembly illustrated in Figure 4, showing the ladder in its operative position and the underside of the slide member.

Figure 7 is a side elevational view of the assembly in which two ladders are arranged so that their lower ends are pivotally connected, the base assembly being capable of use as a sled having runners, and

Figure 8 illustrates the same assembly in yet another form wherein the upright frame members are inclined toward the center and pivotally connected to support a teeter-totter, as illustrated in detail in Figure 2.

As previously stated, the invention is especially designed for ready reformation from one structural unit to another, employing the same parts which are generally in pairs of the same length, and associated so that they may be detached and reassembled with a minimum of effort. It is therefore desirable that the parts may be light, though durable in construction, and connected by bolts or removable pins to simplify the rearrangement of the assembly.

Accordingly, therefore, the base member 10 is constructed with a pair of spaced strips 11 whose ends 12 and 13 are cut diagonally, as particularly illustrated in Figure 1, providing runners, the forward ends 12 of the assembly being cut diagonally downwardly and rearwardly while the rearmost ends 13 have the same diagonal inclination. On top of the frame 10 is arranged a plate or panel 14 of sheet metal, or the like, affording a suitable floor for the assembly and at once providing a floor for a sled which may, as will presently be shown, be utilized as a slide.

A pair of upright members 15 and 16 are arranged on each end of the base 10 and these are spaced apart and connected at their lower ends by bolts or pins 17 and 18 to the strips 11, near their ends 12 and 13 but spaced from the ends a relatively short distance as apparent in Figure 1. The members 15 and 16 incline toward each other and are connected across their upper ends by a pair of spaced strips 19 through the medium of pins or bolts 20 and 21. Two pairs of diagonally arranged bracing members 22 and 23 are connected between the upright members 15 and 16 and the horizontal members 19 by suitable pins or bolts 24 and 25 at their upper and lower ends.

The paired upright members 15 and 16 each have extra sets of apertures 26 and 27 therein whereby to enable the attachment of the parts of different arrangements, as illustrated in the

other figures of the drawings, and in a manner which will be presently described. Extra sets of apertures 29 and 30 are formed in the paired horizontal members 19 also for the purpose of rearrangement of the parts to form different structures.

In the device shown in Figure 1 a ladder 31 is suspended between the horizontal members 19 and is connected by pins 32 thereto and has a series of rungs 33. Supported at the bottom of the ladder 31 is a teeter-totter 34 which is pivotally supported on a rod or pin 35 extending transversely through the ladder 31, a keeper block 36 being attached to the bottom of the member 34 to provide for a variety of adjustments of the ladder on its pivot 35 through apertures 37 and 38.

The teeter-totter member 34 is illustrated in detail in Figure 2 and shows the seats 39 and 40 arranged on each end thereof in which cutouts 41 and 42 are provided to accommodate the legs of children utilizing the equipment. Hand-holes are provided by bars 43 and 44 arranged transversely of the member 34 in front of each of the seats 39 and 40.

A re-arrangement of the parts of the structure is illustrated in Figure 4 in which a slide is provided by moving the diagonal brace members 22 and 23 from the assembly so that the upright structures 15 and 16 can be arranged at different angles, but without disconnecting the bolts or pins 20 and 21 through which these members are attached to the horizontal assembly 19, the members 15, 16 and 19 thus providing a supporting frame structure for the base member 10, which is arranged in an inclined position to provide a slide, the latter being re-arranged in the assembly so that its upper end is connected by the pin 35 through the apertures 27 in the member 15 while its lower end is connected by the pin 32 through one set of the apertures 29 in the horizontal bar assembly 19, the ladder 31 being employed to reach the top of the slide thus afforded.

Other arrangements of the assembly are illustrated in Figures 7 and 8, and in Figure 7 the structure is very much the same as that shown in Figure 1, the arrangement of the parts being identical except that a pair of ladders 31 are arranged in the frame structure so that the upper ends are connected by pins or rods 45 and 46 arranged through the apertures 30 of the horizontally positioned bars 19 and have their lower ends connected by pins or rods 35 to form a substantial V-arrangement for climbing or exercising purposes. The ladders 31 are arranged above the base assembly 10 whose covering plate 14 provides a floor for this assembly. The base structure 10 has a rod 46 arranged across and between the runner 11 to which can be attached a rope 47, or other device, for pulling the assembly as a sled, if desired.

Figure 8 illustrates an arrangement of the parts in which the upright members 15 and 16 are connected at their upper ends by the rod or pin 35 after having been disconnected from

the horizontal assembly 19, in Figures 1 and 7, providing a support for the teeter-totter member 34, shown in Figure 4, and illustrated in the structure shown in Figure 1. The lower ends of the upright members 15 and 16 are attached to the base 10 in the same manner as in the structures illustrated in Figures 1 and 7. If desired, and when the structure is employed as a sled, a box 48, having a seat assembly 49, may be secured at each end by rods or pins 50 to the inclined members 15 and 16, as shown in Figure 8, providing for small children riding a sled which is more adaptably constructed by the arrangement illustrated in Figure 8. The members 48 and 49 are illustrated in dotted lines.

It will readily become obvious that several different arrangements of the parts may be provided, not herein shown and described, and that certain changes and modifications in the design and construction of the apparatus may be resorted to, from time to time, by persons skilled in the art without departing from the spirit and intent of the invention or the scope of the appended claim.

What is claimed is:

A ladder climbing device for use as an exercising apparatus for children, comprising a base unit, said base unit including a pair of spaced parallel runners, and an elongated board spanning and rigidly secured to the runners, said runners having apertures in opposite end portions thereof and projecting beyond opposite ends of the board, pairs of upright perforated bars secured at their lower ends to opposite ends of the runners, a further pair of perforated bars rigidly connecting the upper ends of the first named bars, inclined braces connecting the intermediate portions of the first named perforated bars with the intermediate portions of the second named perforated bars, a pair of ladder units suspended from the second named bars near the opposite ends thereof, and means connecting the lower ends of said ladder units together in adjacent relation.

HOMER R. ROBBINS.
